UNITED STATES PATENT OFFICE.

EARL T. CAMPBELL, OF ELWOOD, INDIANA.

SHEET-FEEDING MACHINE.

1,216,773.

Specification of Letters Patent. Patented Feb. 20, 1917.

Application filed July 24, 1916. Serial No. 110,940.

To all whom it may concern:

Be it known that I, EARL T. CAMPBELL, a citizen of the United States, and a resident of Elwood, county of Madison, and 5 State of Indiana, have invented a certain new and useful Sheet-Feeding Machine; and I do hereby declare that the following is a full, clear, and exact description thereof, reference being had to the accompanying 10 drawings, in which like letters refer to like parts.

This invention relates to improved pneumatic means for feeding sheets of metal and the like singly from a stack to any machine 15 or device to which it is desired to feed them. The invention has been made for use particularly in tin plate factories where it is desired to so feed the black plates from stacks, as they have been taken from the 20 water bath by the tinner, singly to the tinning machine.

One feature of the invention consists of the suction or pneumatic construction for picking up the top sheet of a stack and conveying it to the rolls whereby it is fed into the tinning machine. The frame which carries the suction head also carries the pump and said pump is operated by its movement with said frame so that there is 25 close association and coöperation of the suction frame and pump. This enables an ordinary bicycle pump to be used, the plunger of the pump being reversed and stationary or if desired connected with the shaft which 30 causes the travel of the suction frame. The result is a very simple construction and one which operates in the most desirable manner. Another feature of the invention is the combination with the frame carrying the 35 suction head and pump, of means for giving the same a substantially horizontal movement, and tracks over which said frame is adapted to travel for moving the sheet from the stack to the feed rolls.

40 Still another feature of the invention consists of means actuated by said suction frame near the end of its advancing movement for separating the feed rolls or lifting the upper feed roll so that the plate will readily enter 45 between the feed rolls.

Still another feature of the invention consists in means resting upon the stack of

sheets of black plates for stopping or limiting the rearward or return movement of the suction frame and suction head, so that the 55 suction head will be applied to the top sheet near its front end.

Still another feature of the invention consists in the combination with the suction head and stop plates, of weighted means 60 resting upon the top sheet to the rear of the suction head for holding the top sheet at that point down, while the front end of it is being lifted by the suction head, in order to facilitate the separation of the top sheet 65 from the sheets below in the stack, as the top sheet adheres with considerable force to the sheet below it.

Another feature of the invention consists in a dividing or switch means operated by 70 the suction frame near the end of its advance movement for deflecting the sheets of black plate in their feeding movement so as to send them to different tinning rolls. Thus, in some machines they have a double 75 deck of tinning rolls and with this apparatus every other plate will be fed to the lower set of rolls and the alternate plates fed to the upper set of rolls.

Still another feature of the invention consists in means actuated and controlled by the means for operating the suction frame for feeding or elevating the stack of sheets or plates as the top sheets are being fed therefrom so that when the suction head returns 85 after each operation, the top sheet of the stack will be at the same elevation as the top sheet previously removed. A filler plate is provided in the suction head whereby the air space is reduced to a very small space 90 so that a vacuum is produced immediately upon the movement of the frame. This prevents the suction head from releasing the plate before the air is withdrawn and a sufficient vacuum is produced. 95

The full nature of the invention will be understood from the accompanying drawings and the following description and claims:

In the drawings, Figure 1 is a side elevation of the machine, with the pneumatic feeding means partially operated so that the forward end of the top sheet has been 100 separated and elevated from the feed below.

Fig. 2 is a plan view of the machine with the parts in idle position or in the position before or at the beginning of an operation thereof. Fig. 3 is a vertical section through the machine on the line 3—3 of Fig. 2, showing in addition, however, a sheet or plate passing through the feed rolls after the return of the pneumatic feeding means. Fig. 4 is a reproduction of portions of Fig. 3 showing the position of the parts when the suction frame has reached its advanced position and the sheet or plate has been placed between the feed rolls so that a further movement of the pump will release the suction head and return the suction frame, and the divider being elevated so that the feed rolls will feed the sheet to a lower set of tinning rolls. Fig. 5 is a side view of a portion of the right-hand end of the machine shown in Fig. 1, but in altered position and on a larger scale, Fig. 1 showing the divider operating means in position for elevating the divider to the position shown in Fig. 4 for feeding the sheet to the lower set of tinning rolls, while Fig. 5 shows the parts in their position when the divider is down so as to deflect the plates to the upper set of tinning rolls. Fig. 6 is a horizontal section through a portion of the machine, as shown in Fig. 2, illustrating the mounting of one end of the upper feed shaft, the remaining parts being broken away. Fig. 7 is a vertical section on the line 7—7 of Fig. 1, through the upper portion of the machine. Fig. 8 is a reproduction of the right-hand end of what is shown in Fig. 4 with some parts in section to illustrate the position of the parts when the suction head releases its hold on the sheet or plate being fed forward to the feed rolls. Fig. 9 is a vertical central section through the suction head in idle position. Fig. 10 shows the same when under suction.

There is shown herein only a part of the framework of the machine, as it is immaterial just how the framework is constructed. In fact, there is shown herein two frames 10 and 110 which, however, are mounted in fixed relation to each other. The frame 10 carries a crank shaft 11 driven by a pulley 12 and belt 13 coming from some suitable source of power. There is also mounted in one side of said frame a pulley 14 driven by a belt 15 running over cone pulleys 16 and 17, whereby power is transmitted from the pulley 12 to the pulley 14 and power is transmitted from the pulley 14 through a belt 18, shown by dotted lines in Fig. 3, to a pulley 19 on a shaft 20 which is mounted in the other frame 110 and whereby the feed rolls are driven, one feed roll 21 being secured on said shaft 20 and the other feed roll 22 shown mounted above it on a shaft 23.

The work of this machine is to feed the

top sheet or plate from the stack 25 to the feed rolls 21 and 22 so that said feed rolls can feed such sheet or plate to some other device, as in tin plate factories to the tinning rolls. The stack of plates is carried on a table 26 and by means hereafter described maintained so that the top plate will be on a level with a stationary plate or table 27 which leads from the stack of plates to the feed rolls. This plate 27 has a lip or flange 28 extending upwardly from the end next to the stack to a level slightly higher than the top sheet of the stack. There are also rollers 29 carried by said plate 27 near the stack and the top sheet is picked up near its front end and dragged over the rollers 29 and inserted between the feed rolls 21 and 22, as shown in Fig. 4. To accomplish this result, therefore, it is necessary first to separate the top sheet from the sheet below it; second, to elevate the advancing end of said sheet so that it will pass over the lip 28 and the rollers 29; and third, drag it or move it to the feed rolls.

The means for accomplishing the foregoing consists of a suction head 30 adapted to engage and pick up the forward end of the top plate and transfer it to the feed rolls. This suction head is formed, as shown in Fig. 9, of a cylindrical filler 31 covered by a metal sheet plate to which a flexible suction tube 32 is connected by a coupling 33. The metal plate covering has a laterally extending and downwardly sloping flange on which a rubber ring 34 is held by the clamping means 35. When air is exhausted from the suction head, it will be dropped down close to the plate, as shown in Fig. 10, and the rubber ring 34 caused to adhere tightly to the plate.

On the suction head 30 there are two ears 36, seen in Fig. 7, through which a rod 37 extends transversely of the machine. Said rod is carried in and is a part of the suction frame 38. This frame is composed of two vertical bars connected by a horizontal bar at the upper end so that the frame is rectangular. An arm 39 extends centrally from the upper end of said frame and has an eye at its upper end through which a stop rod 40 extends which is pivoted at one end to the crank shaft 11 and at its other end has a head or stop 41 thereon, see Fig. 8.

Said suction frame is pivoted or suspended near its upper end on a transverse rod 42, as seen in Fig. 7, and a pair of actuating bars 43, see Fig. 2, are pivoted at their front ends to the rod 42 and at their rear ends to the cranks 44 of the crank shaft 11 so that as said crank shaft is rotated, the cranks thereof through the bars 43 will force the rod 42 and the suction head carried by it from the rearmost or retracted position, shown in Figs. 2 and 3, to the posi-

tions shown in Figs. 1, 4 and 8, successively, and return said suction head.

The rod 42 has on its ends wheels or rollers 45 arranged so as to travel on the tracks or guideways 46 of which there is a pair, as shown in Fig. 2, and mounted in connection with the frame 110, as shown in Fig. 3. These tracks are first inclined upwardly in order to elevate the suction head and sheet to separate the sheet from the stack and carry it over the rollers 29 and then the tracks are inclined downwardly to bring the sheet into position between feed rolls 21 and 22.

The suction is created by an ordinary bicycle pump consisting of a cylinder 50 carried at its forward end by the rod 42, as shown in Fig. 7, in the suction frame, and at that end connected with the suction tube 32. The other end of the cylinder 50 is open having on it a spider 52 through which the rod 53 of a piston or plunger 54 operates. Said rod is connected with a yoke-shaped frame 55 which is pivoted on the crank shaft 11, as seen in Fig. 2. With this arrangement, the piston 54 always remains stationary, while the cylinder is moved longitudinally by the suction frame as it travels from the position shown in Fig. 3 to that shown in Fig. 8. In other words, suction action commences as soon as the cranks 44 on the crank shaft begin to turn downward from their rearward position, shown in Fig. 2, and as soon as the suction frame begins to move forward, the suction action commences. Since the suction frame, as seen in Fig. 3, is pivotally mounted at its lower end on the rod 37, the upper end of said frame moves or oscillates, while the lower end and suction head are stationary and this continues until the suction frame begins to travel up on the brackets 46, as shown in Fig. 1, and then the suction frame will elevate the suction head and the suction head will elevate the forward end of the top sheet or plate from the stack, as shown in Fig. 1. Hence, with this arrangement, there is sufficient movement of the upper part of the suction frame to cause the pump to operate long enough to create the necessary suction to enable the suction head to grasp and hold the top plate and before there is any vertical movement of the suction head.

When the suction frame has been advanced to the position shown in Fig. 8, the pump cylinder 50 will have traveled so far to the right that the piston 54 will have passed a port or hole 56 in said cylinder which will admit air into the cylinder and suction tube 32 and the suction head and cause the latter to release the sheet or plate. Then the suction frame is returned.

When the suction frame approaches the end of its advancing movement to the posi-

tion shown in Fig. 4, it will engage the arms 65 or levers 60 secured on a shaft 61 mounted in the frame 110, see Figs. 4 and 7. Two short arms 62 are secured on the shaft 61, as seen in Fig. 4, and to them vertical rods 63 are pivoted at their upper ends. Said rods 63 at their lower ends are connected with a bearing 64 for the ends of the upper feed roll shaft 23, which bearing is vertically slidable in a bracket or frame 65, see Figs. 6 and 7. This will elevate the upper feed rolls from the lower feed rolls, as seen in Figs. 4 and 8, and permit the advancing end of the sheet to pass between said rolls.

When the suction frame 38 is returned to the position shown in Fig. 3, its lower end is stopped by two vertical plates 70, see Figs. 3 and 7, which engage the transversely extending rod 37 connected with said suction frame and thus cause the suction head to rest upon the top plate near the front end thereof. These plates 70 are secured on a transverse rod 71, see Fig. 2, carried in the ends of rods 73 which extend forward and are pivoted at 74 in the opposite side of the frame 110. Said rod 71 is weighted by a weight 75 between its ends and at each end carries a roller 76. The roller 76 rests upon the top sheet or plate to the rear of the suction head and the gravity of said rollers and associated parts tends to hold said top plate or sheet down upon the next sheet while the suction head is lifting the forward end of said top sheet away from the sheet below, as illustrated in Fig. 1. This arrangement is to facilitate the separation of the top sheet from the sheet below as they strongly adhere together when in the stack.

The means which causes the feeding of the top sheet from the stack to the feed rolls also causes or actuates the means for elevating the stack to maintain the top sheet on a proper level for the successful operation of the suction head. The table 26 which carries a stack is supported on two disks 160 on the upper ends of screw rods 161 on which worm wheels 162 are adjustably secured in proximity to each other so that both worm wheels will be driven by a conical worm shaft 163. A frame 164 furnishes bearings 165 for the screw rods 161 and the work wheels 162 and also for the worm shaft 163, see Fig. 3. As shown in Fig. 1, the worm shaft 163 is actuated by a ratchet wheel 66 secured thereon and a pawl 67 on a lever 68 fulcrumed concentric with the ratchet wheel and given a step by step movement by a rod 69 extending therefrom and adjustably secured in a slot 170 in an arm 171 secured on the outer end of the crank shaft 11. As said arm 171 revolves in the direction of the arrow in Fig. 1, the ratchet wheel 66 is given a partial rotation

so that it causes an elevation of the screw rods 161 and table 26 equal to the thickness of one sheet or plate 25 in the stack.

For dividing the sheets or plates as they leave the feeding mechanism so as to deliver them alternately to the lower or upper set of tinning rolls, the following mechanism is provided. On an extension 80 to the frame 110 there is a shaft 81, see Fig. 2, having secured on it dividing arms 82 triangular in shape and with the apex projecting toward the bite of the feed rolls. On the outer end of said shaft 81 there is a crank arm 83, see Figs. 1, 2 and 5. It is limited in its downward movement by a stop 84, as shown in Fig. 5, and when in that position, the dividing arms are in the position shown in Fig. 3, so that the sheet will be fed to the upper set of tinning rolls. A spring 85 tends to hold and return said arm 83 to its downward position, as shown in Fig. 5. A ratchet wheel 86 is mounted on the outside of the frame 110, see Fig. 5, and is actuated by a pawl 87 on a bar 88 vertically reciprocable in the guides 89 secured on the frame 110. Said bar is actuated by a connecting bar 90 extending therefrom up to an arm 91 on the shaft 61, like the arm 62, see Fig. 4. When the bar 88 is moved upward, it actuates the ratchet wheel 86 and to said ratchet wheel a bar 92 is diametrically secured carrying pins 93 near the ends thereof in position to engage the free end of the arm 83 and elevate and actuate it from the position shown in Fig. 5 to the position shown in Fig. 1, and that moves the dividing arms 82 from the position shown in Fig. 3 to the position shown in Fig. 4, and then the sheets or plates will be fed by the feed rolls to the lower set of tinning rolls. The actuating means just described is so arranged as to switch said dividing arms 82 from one position to the other as each sheet or plate approaches the same so that they will be alternately delivered to the upper and lower sets of tinning rolls. The frame 110 has a pawl 94 pivoted thereon in position to engage the ratchet wheel 86 and prevent its backward movement.

50 The invention claimed is:

1. A sheet feeding machine including a suction head, a suction frame for carrying said head in position to engage and move a sheet, suction means carried by said frame and in communication with the suction head and stationary means with which said suction means is connected arranged so that the movement of the suction frame causes the operation thereof.

60 2. A sheet feeding machine including a suction head, a suction frame for carrying said head in position to engage and move a sheet, a suction pump carried by said frame and in communication with the suction

head, and stationary means with which said pump is connected arranged so that the movement of the suction frame causes the operation of the pump.

3. A sheet feeding machine including a suction head, a frame for carrying said head so as to engage and move a sheet, a suction pump carried by said frame and operated by the movement thereof in communication with the suction head, a crank shaft, and means driven by said shaft for causing the movement of said suction frame.

4. A sheet feeding machine including a suction head, a frame for carrying said head so as to engage and move a sheet, a pump cylinder mounted in said suction frame in communication with the suction head, a piston in said cylinder adapted to be held in a relatively fixed position, a crank shaft, and means driven by said shaft for causing the movement of said suction frame.

5. A sheet feeding machine including a suction head, a frame for carrying said head so as to engage and move a sheet, a pump cylinder mounted in said suction frame in communication with the suction head, a piston in said cylinder adapted to be held in a relatively fixed position, a crank shaft, and means driven by said shaft for causing the movement of said suction frame, said pump cylinder being provided with an opening near the limit of the forward movement of said suction frame for admission of air into the pump to cause the suction head to release the sheet.

6. A sheet feeding machine including a suction head, a frame for carrying said head so as to engage and move a sheet, a pump cylinder mounted in said suction frame in communication with the suction head, a piston in said cylinder adapted to be held in a relatively fixed position, a crank shaft, and bars pivoted on the cranks of the crank shaft and pivotally connected with the sides of said suction frame for actuating the latter.

7. A sheet feeding machine including a suction head, a frame for carrying said head so as to engage and move a sheet, a pump cylinder mounted in said suction frame in communication with the suction head, a piston in said cylinder adapted to be held in a relatively fixed position, a crank shaft, means driven by said shaft for causing the movement of said suction frame, and means for limiting the advancing movement of the upper end of said suction frame.

8. A sheet feeding machine including a suction head, a frame for carrying said head so as to engage and move a sheet, a pump cylinder mounted in said suction frame in communication with the suction head, a piston in said cylinder adapted to be held in a relatively fixed position, a crank shaft,

means driven by said shaft for causing the movement of said suction frame, an upward extension from the suction frame having an eye in its upper end, a rod pivoted to the 5 crank shaft and extending through said eye, and a stop on the outer end of said rod for limiting the advancing movement of said extension from the suction frame.

9. A sheet feeding machine including a 10 suction head, a suction frame carrying said head, suction creating means carried by said frame and in communication with the suction head and adapted to be operated by the movement of said frame, means for moving 15 said frame, and inclined tracks on which said frame travels arranged to elevate said frame and suction head to enable the latter to lift the top sheet from a stack of sheets and carry the same to the desired point of 20 release.

10. A sheet feeding machine including a suction head, a suction frame carrying said head, suction creating means carried by said frame and in communication with the suction 25 head and adapted to be operated by the movement of said frame, means for moving said frame, rollers at each side of said suction frame, and tracks on which said rollers are adapted to travel as said frame 30 moves forwardly, said tracks being first upwardly inclined to lift the suction head and the sheet attached thereto.

11. A sheet feeding machine including a suction head, a frame for carrying the same, 5 means for causing the travel of said frame after the sheet has been engaged by the suction head for conveying the sheet as desired, and means resting upon the next sheet to be conveyed and in position to engage and 10 stop the return movement of said suction frame so as to place the suction head near the end of a sheet.

12. A sheet feeding machine including a suction head, a frame for carrying the same, 5 means for causing the travel of said frame after the sheet has been engaged by the suction head for conveying the sheet as desired, means resting upon the next sheet to be conveyed and in position to engage and stop the 10 return movement of said suction frame so as to place the suction head near the end of a sheet, and weighted means on said sheet to the rear of the suction head for holding said rear portion of the sheet down while the forward end of the sheet is being elevated by the suction head.

13. A sheet feeding machine including a frame, a table on which a stack of sheets may be placed adjacent said frame, a suction head, a suction frame for carrying said head and placing the same on the top sheet of a stack, means for moving said suction frame after the suction head has grasped the top sheet of the stack, a rod extending

transversely of the stack with forwardly extending means pivoted to said frame, rollers on said rod for resting upon the top sheet of the stack to the rear of the suction head, and vertically disposed plates on said rod and resting upon the top sheet of the stack in position to engage the suction frame on its return movement and stop the suction head on the forward part of the top sheet of the stack.

14. A sheet feeding machine including a 75 main frame, a suction head, a suction frame carrying the suction head, a crank shaft, means actuated by the crank shaft to operate the suction frame, a table for holding a stack of plates in position for the top 80 plates to be picked up and transferred by the suction head, vertically movable rods for supporting said table, worm gears for actuating said rods, a worm shaft for actuating said gears, a pawl and ratchet drive for actuating said worm shaft, and means driven by the crank shaft for operating the pawl and ratchet drive, said means being geared and arranged so that the table will be moved 85 upwardly as the sheets are fed therefrom so that the top sheet of the stack of sheets will 90 always be at uniform height.

15. A sheet feeding machine including a 95 frame, a pair of feed rolls for feeding the sheets to any suitable mechanism, the upper feed roll being vertically movable, a lever and connecting rod for vertically moving said roll, a suction head for engaging and transferring a sheet to said rolls, a suction frame carrying said suction head and means 100 for actuating said suction frame carrying said suction head, so that it will, near the limit of its movement, engage said lever and elevate the upper feed roll so that the plate being fed can enter between the feed rolls.

16. A sheet feeding machine including a 105 frame, a pair of feed rolls mounted in the frame, means for feeding sheets to said feed rolls, horizontally disposed dividing fingers fulcrumed in the frame in position when turned downward to cause a sheet to pass above said fingers and when elevated to permit the sheet to pass below the fingers, and means actuated by the sheet feeding means 110 for alternately elevating and lowering said dividing fingers.

17. A sheet feeding machine including a frame, a pair of feed rolls mounted therein, means for feeding sheets successively to the feed rolls, a horizontal shaft mounted in advance of the rolls, dividing fingers secured on said shaft and extending toward the bite of the rolls, a vertically movable bar moved upward by the sheet feeding means, a pawl pivoted thereon, a ratchet wheel mounted on the frame to be engaged and actuated by said pawl, an arm secured to said shaft, a bar secured to the ratchet wheel in 115 120 125

position to engage said fingers and permit a sheet to pass below the dividing fingers, and a spring for turning said shaft and dividing fingers to their downward position 5 so that the sheet will pass above said dividing fingers.

In witness whereof, I have hereunto af-

fixed my signature in the presence of the witnesses herein named.

EARL T. CAMPBELL.
